UNITED STATES PATENT OFFICE

ROY W. JOHNSON, OF COLUMBUS, OHIO, ASSIGNOR TO CHECKER CAB MANUFACTURING CORPORATION, OF KALAMAZOO, MICHIGAN, A CORPORATION OF NEW JERSEY

DESIGN FOR A PILLAR ROOF LAMP

Application filed November 3, 1930. Serial No. 37,515. Term of patent 3½ years.

To all whom it may concern:

Be it known that I, Roy W. Johnson, a citizen of the United States, residing at Columbus, in the county of Franklin and State of Ohio, have invented a new, original, and ornamental Design for Pillar Roof Lamp, of which the following is a specification, reference being had to the accompanying drawings, forming a part thereof.

Figure 1 is a front elevation of the lens frame of the pillar roof lamp showing my new design,

Figure 2 is a side elevation thereof showing the same in connection with the body of the lamp, and

Figure 3 is a perspective view of the lens frame shown from the front thereof.

I claim:

The ornamental design for a pillar roof lamp, as shown.

ROY W. JOHNSON.
